UNITED STATES PATENT OFFICE.

WILLIAM W. RANDOLPH, OF NEW ROCHELLE, NEW YORK.

SPRAYING-NOZZLE.

SPECIFICATION forming part of Letters Patent No. 625,466, dated May 23, 1899.

Application filed April 22, 1898. Serial No. 678,481. (No model.)

To all whom it may concern:

Be it known that I, WILLIAM W. RANDOLPH, a citizen of the United States of America, residing in New Rochelle, county of Westchester, in the State of New York, have invented a certain new and useful Improvement in Spraying-Nozzles, of which the following is a true and exact description, reference being had to the accompanying drawings, which form a part thereof.

My invention relates to the construction of nozzles for spraying water or other fluids, and has for its object to provide a spraying-nozzle which will provide for a more even distribution of the spray over a circular core than has heretofore been practicable.

My spraying-nozzle belongs to the class in which the spraying of a fluid issuing through the nozzle with considerable velocity is effected by giving it a rotary motion in the nozzle, so that as it issues therefrom the motion of each particle of fluid is effected by the two forces, one tending to carry it forward and the other tending to throw it outward tangentially, and the result of the two forces being, as is well known, to throw the body of fluid into an expanding cone and rapidly break it up into spray; and my invention consists in using in a nozzle in place of a single angular deflector for giving rotary motion to the fluid a series of concentric angular deflectors arranged to operate upon concentric bodies of fluid passing through the nozzle and to give to each body a direction resulting from the two forces acting upon it, which will result in a more even and uniform distribution of the composite jet. Preferably I make the concentric deflectors of progressively higher pitch from the center outward, so that the successive conical jets will be of progressively greater angle, and preferably also I provide, in addition to the concentric deflecting devices, a corresponding series of concentric delivery-nozzles through which the fluid passes after leaving the deflecting devices and before its issuance from the nozzle.

Reference is now had to the drawings, in which my invention is illustrated, and in which—

50 Figure 1 is a side elevation of the nozzle constructed in accordance with my invention,

showing the character of the composite jet. Fig. 2 is a rear view of the inside of the spraying-nozzle. Fig. 3 is a longitudinal section taken as on the line xx of Fig. 2; and Figs. 4, 5, and 6 are dissociated perspective views of the deflecting devices and their attachments.

A indicates a fluid-conduit leading, as shown, to a valve-casing B, C indicating the valve-handle, and through the valve-casing and a pipe-section D to the nozzle, (indicated at F,) the outer casing of the said nozzle being, as shown, screwed into a threaded enlargement E of the pipe D.

The nozzle, as shown, is at its outer end divided into three concentric nozzle-sections the walls of which are formed by the tubes F, G, and H, and at the base of each of these sectional delivery-nozzles is situated a device for giving a rotary movement to the particular body of fluid passing into each nozzle-section. As shown and as conveniently constructed, the tube G is provided with an outwardly-extending flange G', fitting against a shoulder f of the tube F and formed with angular slots g', through which the fluid passes and by which it is given a rotary movement as it passes into the annular space between the tubes F and G. The tube H is provided with a similar base-flange H', fitting against the shoulder g at the base of the tube G and provided with angular deflecting-slots h', which give the desired rotative movement to the fluid as it passes into the chamber between tubes G and H.

I is a circular block adapted to fit against shoulders h at the base of the tube H, and formed with angular deflecting-slots i, which give the desired rotative movement to the fluid as it passes into the tube H.

It will be observed that I have shown the deflecting-slots i, h', and g' as of progressively increasing angularity, this being done so as to make the sides of the cones (indicated at I², H², and G², Fig. 1) of progressively greater angularity, the arrangement being potential and preferably such as to make the composite cone of substantially uniform density.

It is obvious, of course, that the effective agents in giving the fluid a rotary motion are the angularly-set walls separating the grooves h' g' i and which may properly be considered

as partitions arranged in concentric annular delivery-sections of the nozzle.

Having now described my invention, what I claim as new, and desire to secure by Letters 5 Patent, is—

1. A spraying-nozzle having two or more concentrically - arranged delivery - sections each provided with angularly-set deflector-partitions whereby separate concentric bodies 10 of fluid issuing from the spraying-nozzle are given a rotary motion.

2. A spraying-nozzle having two or more concentrically - arranged delivery - sections each provided with angularly-set deflector- 15 partitions, the partitions in the different sec-

tions being of progressively greater pitch or angularity from the center outward.

3. A spraying-nozzle having two or more concentrically - arranged delivery - sections each provided with angularly-set deflector- 20 partitions whereby separate concentric bodies of fluid issuing from the spraying-nozzle are given a rotary motion and concentric delivery-tubes through which the rotating bodies of fluid escape from the spraying-nozzle.

WM. W. RANDOLPH.
